The Perfect Circle Company, Hagerstown, Ind.,
a corporation of Indiana

Application December 21, 1939, Serial No. 89,065

Term of patent 14 years

To all whom it may concern:

Be it known that I, Lothair Teetor, a citizen of the United States, residing at Hagerstown, in the county of Wayne, State of Indiana, have invented a new, original, and ornamental Design for a Display Rack for Pistons and Connecting Rod Assemblies, of which the following is a specification, reference being had to the accompanying drawing, forming a part thereof, wherein—

Fig. 1 is a perspective view of a display rack

for pistons and connecting rod assemblies, showing my design;

Fig. 2 is a side elevational view of the same;
and

Fig. 3 is an end elevational view of the same.

I claim:

The ornamental design for a display rack for pistons and connecting rod assemblies, as shown.

LOTHAIR TEETOR.
